VACUUM-BOTTLE CASING.

1,147,632.

Specification of Letters Patent. Patented July 20, 1915.

Application filed March 24, 1914. Serial No. 826,902. **REISSUED**

To all whom it may concern:

Be it known that I, JOSEPH F. LAMB, a citizen of the United States, and a resident of New Britain, in the county of Hartford, 5 State of Connecticut, have invented certain new and useful Improvements in Vacuum-Bottle Casings, of which the following is a specification.

The object of this invention is to produce 10 a casing for vacuum bottles and the like, having features of novelty and advantage.

In the drawings—Figure 1 is a central vertical section of a casing embodying my invention. Fig. 2 is a side elevation thereof, 15 with the cap broken away.

Referring to the drawings, *a* denotes the main body of the casing having a slight enlargement *b* at its upper end, the upper edge of the casing being exteriorly and interiorly threaded as indicated at *c*. These casings are made of sheet metal and the thread can be conveniently formed by rolling. The vacuum bottle *d* fits within the casing and is preferably yieldingly supported as for instance by the structure indicated generally by *e*, comprising a coiled spring to take end thrust, and elastic up-standing arms contacting with the bottle and the casing to take side thrust. The neck of the bottle is engaged by the inwardly curved end of the sleeve 10, between which and the bottle there is positioned a yielding gasket 11, and the lower end of this sleeve is threaded and fitted to the inner threads at the top of the casing. These threads on the casing and on this sleeve are of substantial length in order that the variations in the length of the bottles can be accommodated, and the bottle properly seated in the yielding support within the casing to avoid breakage. A cap 15 which may be used as a cup is threaded and fitted to the exterior threads at the upper end of the casing, forming a complete closure for the upper end of the casing and a protector for the cork or other stopper which is fitted into the mouth of the vacuum bottle.

By the hereinabove described arrange-

ment of the parts there is provided a very secure means for holding the bottle 50 in the casing, a means which is adjustable to accommodate variations in the sizes of the bottles. The securing sleeve being threaded into the interior of the casing, and the cap threaded onto the exterior of the 55 casing but free from the sleeve, permits of the cap being applied to and taken from the casing without disturbing the bottle in any way.

I claim as my invention:

1. In a device of the character described, the combination with a casing and a vacuum bottle located therein, of a sleeve engaging the neck of said bottle projecting through the top of said casing and adjustable thereon relatively to said bottle, and an inclosing cap connected with said casing independently of said sleeve. 60

2. In a device of the character described, a main body part open at its upper end and provided thereat with exterior and interior threads, a rotatable sleeve projecting through the top of said body, connected thereto by the interior threads and engaging and adjustable relatively to a bottle 75 supported in said main body, and a cap connected to said body by the exterior threads. 70

3. In a device of the character described, the combination with a sheet metal casing 80 formed in one piece and provided at its open end with a single thread presenting interior and exterior engaging surfaces, and a vacuum bottle located within said casing, of a sleeve engaging the interior surface of 85 said thread and projecting through the top of said casing to engage the neck of said bottle, and an inclosing cap engaging the exterior surface of said thread, said sleeve and cap being detachable independently of 90 one another and said sleeve adjustable relative to said bottle.

JOSEPH F. LAMB.
